INSIDE-OUTSIDE METAL TRIM

Clyde W. Kelly, Detroit, Mich., assignor to Detroit Steel Products Company, Detroit, Mich., a corporation of Michigan

Application March 27, 1950, Serial No. 152,109

12 Claims. (Cl. 189—75)

1

The present invention relates to inside-outside metal trim for window openings, and more particularly to metal trim adapted to be assembled on the job and inserted as a unit into a rough window opening.

It is an object of the present invention to provide inside-outside metal trim of the character described designed to facilitate forming, assembly, and mounting of the trim.

It is a further object of the present invention to provide trim of the character described which is attractive in appearance, easy to mount in a rough window opening, and is designed to serve as the supporting means for a sash frame.

It is a feature of the present invention to provide inside-outside metal trim composed of head, jamb, and sill members with their ends shaped to interfit and interlock so as to produce a rigid rectangular frame.

It is a further feature of the present invention to provide a frame as described above, characterized by the provision of channel shaped moldings at both the room side and the weather side, the channel shaped moldings at the room side having an outer leg designed to serve as a plaster stop, the moldings at the weather side on the head and jamb members constituting reveals, the molding on the sill member including a wash, all of the moldings at the weather side having outwardly extending nailing fins by means of which the frame is secured in the window opening.

It is a further feature of the present invention to provide elongated sheet metal members from which a trim frame is assembled, each of the members having at its opposite sides channel shaped moldings, and means for securing the adjacent corners of some of said members comprising cutout portions located in the moldings of some of said members and cutout portions located intermediate the moldings in the other of said members, and preferably interfitting tongue and slot connections between said members.

Other objects and features of the invention will become apparent as the description proceeds, especially when taken in conjunction with the accompanying drawings, wherein:

Figure 1 is a perspective view partly in section illustrating an assembled trim frame.

Figure 2 is a fragmentary perspective view, partly in section of a sill member.

Figure 3 is a fragmentary view partly in section of a jamb member.

Figure 4 is a fragmentary exploded perspective view illustrating the interlock provided between

2

an end of a head member and an upper end of a jamb member.

Figure 5 is a fragmentary plan view of the end of a head member.

5 Figure 6 is an end elevation of a head member.

Figure 7 is a transverse vertical section through a portion of the building illustrating the inside-outside trim in place.

Figure 8 is a fragmentary horizontal section showing one of the jamb members in place in a window opening.

Figure 9 is a perspective view of an attaching clip used in the present construction.

The inside-outside metal trim comprises an elongated sill member 10, jamb members 12, and a head member 14. These members are formed of sheet metal and excellent results have been obtained when the sill member is formed from 16-gauge steel and the jamb and head members are formed from 18-gauge steel.

15 The head and jamb members are of the same general cross-section and each comprises a room side channel shaped molding 16 having an inner leg 18, and outer leg 20, and an intermediate connecting wall 22. In use, the edge 24 of the outer leg 20 abuts the inner wall of the building and constitutes a plaster stop.

20 At the weather side the members comprise channel shaped moldings 26 which include inner legs 28, outer legs 30, and an intermediate connecting wall 32. The moldings 26 constitute reveals in the assembled frame. At the edge of the outer legs 30 of the weather side moldings 26, the material is formed to extend outwardly 25 to provide nailing fins 34 provided with nailing holes 36.

25 Intermediate the room side moldings 16 and the weather side moldings 26 is an intermediate web portion including a wall 38 and an inwardly 30 extending hollow rib 40, this rib comprising an inwardly extending wall 42, a second inwardly extending wall 44, and an intermediate connecting wall 46. The walls 38 and 42 define relatively deep recesses for shades or blinds and this 35 constitutes an important feature of the present construction.

At the weather side of the hollow ribs 40 and between such ribs and the channel shaped reveal moldings 26, the material of the head and sill members is shaped to provide walls 47 and 48, the walls 44 and 47 providing seats against which flanges of sash frame bars 49 seat as indicated in Figures 7 and 8. The wall 48 is provided with threaded openings 51 for the reception of fastening screws indicated at 52 in Figure 7. Alter-

natively, the openings 51 need not be threaded and may cooperate with self-threading metal screws.

The sill member 10 includes a channel shaped molding 53 at the room side which comprises an inner leg 54 and an outer leg 56, and an intermediate connecting wall 58. At the weather side the sill member 10 comprises a channel shaped molding 60 having an inclined inner leg 62, an outer leg 64 and an intermediate wall 66. The inclined inner leg 62 constitutes the wash. The outer leg 64 has an outwardly formed nailing fin 67.

Intermediate the channel shaped moldings 53 and 60 extends a web comprising a flat horizontal sill portion 68 terminating in a wall 70 which connects to the inner leg 62 of the channel shaped molding 60. The intersection between the walls 62 and 70 provides a seat in which one flange of the bottom frame member 72 engages as best seen in Figure 7.

Means are provided for assembling the head, jamb, and sill members together on the job so that these members may be transported in collapsed condition at a considerable saving in shipping charges. For this purpose the ends of the members are shaped to cooperate so as to provide a rigid frame and this construction will now be described in detail.

Referring now to Figures 3 and 4, the connection between one of the jamb members 12 and the head member 14 is illustrated. The intermediate portion at the end of the jamb member 12 between the room side molding 16 and the weather side molding 60 is cut back as indicated at 74 to leave tongues 76 and 78, the wall 38 terminating along the edge 80 intermediate and adjacent the tongues 76 and 78. The edge 80 in the assembled frame is adapted to abut against the wall 38 of the head member 14 and the wall 38 of the head member 14 is provided with slots 82 for the reception of the tongues 76 and 78. The ends of the jamb members 12 are further cut away as indicated at 84 across the rib 40 to provide a second end edge portion 86 which is adapted to abut against the wall 66 of the hollow rib 40 in the head member 14. The cut away end portion of the jamb members is continued in a different vertical plane across the walls 47 and 48 as indicated at 88, the end surface thus provided being adapted to fit against the wall portion 48 of the head member 14. Projecting outwardly from the edge 86 is a tongue 90 and the adjacent end of the head member 14 is provided with a slot 92 for the reception of the tongue 90.

The end of the head member 14 is formed with open ended slots 94 and 96 located in the inner leg of the moldings 16 and 26 respectively. The nailing fin 34 projects outwardly beyond the end surfaces of the weather side molding as indicated at 97 (Figure 4).

The previously described end construction of the jamb members 12 leaves portions of the moldings 16 and 26 thereon which extend upwardly and are adapted to enter into the slots 94 and 96 respectively. For this purpose the lateral dimension of the moldings 16 and 26 on the jamb members 12 is slightly smaller than the corresponding dimension of the moldings on the head member 14. This construction provides for proper registry between the ends of the head member 14 and the upper ends of the jamb members 12, the upwardly projecting portions of the moldings on the jamb members entering the slots 94 and 96

provided in the inner legs of the moldings and closing the ends of the moldings 16 and 26. The tongues 76, 78 and 90 enter the slots 82 and 92 and are adapted to be clinched over as best illustrated in Figure 1. Thus, a firm connection is established between the upper ends of the jamb members 12 and the ends of the head member 14.

A different construction is provided for securing the lower ends of the jamb members 12 to the ends of the sill member 10. The ends of the sill member, as best seen in Figure 2, are produced by cutting the sill member and bending certain portions thereof, as will now be described. The room side portion of the sill member at each end thereof is cut away along a plane to provide an edge 109 except for a projecting tab 102 extending from the wall 59 of the inner trim molding 53. This tab 102 is bent as indicated in Figure 2 to close the end of the room side trim molding 53. The weather molding 60 is cut off along a plane spaced from the plane defined by the edge portions 100 to provide second edge portions 104 and 106, at the outer wall 64 and the inner wall or wash 62 respectively. A tab 108 is left extending on the vertical bottom wall 66 of the weather side molding and this is folded over to close the end of the molding as best illustrated in Figure 2. Tabs 102 and 108 are formed to extend into the moldings 53 and 60 respectively. The nailing fin 67 extends longitudinal beyond the weather side molding 60. The wall 68 is provided with a plurality of slots 110 for the reception of tongues provided at the lower end of the jamb members 12.

The lower ends of the jamb members 12, as best seen in Figure 3, are cut away along a perpendicular plane from the room side molding 16 to the wall 42, leaving an end edge surface 112 adapted to rest upon the flat surface of the wall 63 of the sill member 10. The wall member 47 and the inner leg 28 and wall 32 of the weather side molding 26 are cut away along a stepped plane to provide an edge 114 adapted to rest upon the wash or wall 62. The outer leg 30 of the weather side molding and the nailing fin 34 extend downwardly beyond the edge 114. Extending downwardly from the edge portion 112 of the jamb members 12 are tongues 116 adapted to enter into the slots 110 previously described and to be clinched after insertion therein.

When the jamb members 12 are assembled with the sill member 10 it will be observed that there is substantially continuous engagement between the end surfaces of all portions of the jamb members, with the exception of the outer leg 30 of the weather side molding and the nailing fin 34, with corresponding areas provided at the upper surface of the sill member 10. Moreover, the outer leg 30 of the weather side molding and the end of the nailing fin 34 engage in substantial area contact with the bent tab 102 and the end of the nailing fin 67, as best seen in Figure 1.

Referring now to Figures 7 and 8 there is illustrated the manner in which the inside-outside trim is associated in the window opening. In these figures a rough window opening is illustrated at 120. In Figure 7, which is a vertical section through the window, the head member 14 and the sill member 10 are illustrated in section. The nailing fin 34 of the head member 14 is shown nailed at 123 to sheathing 122. The room side molding 16 includes the outer leg 20 which serves as a plaster stop and in this figure plaster is indicated at 124 finished against the surface of the plaster stop 20.

In like manner, the nailing fin 67 of the sill member 10 is nailed to the sheathing 122 as indicated at 125.

In order to retain the inside-outside trim in position attaching clips 130 are provided having heads 132 adapted to fit into the channels of the room side moldings 16 and 53. In practice, the entire assembly is inserted from the outside of the building. At this time the room side moldings 16 and 53 extend into the room beyond the window opening. The heads 132 of the attaching clips 130 are then inserted within the moldings after which the strips are nailed to the building wall.

Attention is directed to the fact that the inside-outside trim not only provides a very attractive finishing trim to both the room side and weather side of the window opening, but also, it may be assembled on the job and inserted with a minimum of effort and without the requirement for skilled labor. Furthermore, the inside-outside trim as described herein is adapted to receive and provide the support for the sash frame. As seen in Figures 7 and 8 the sash frame constitutes a plurality of bars 49, 72 and 136, which are secured against appropriately shaped seats provided by the trim.

The drawings and the foregoing specification constitute a description of the improved inside-outside metal trim in such full, clear, concise and exact terms as to enable any person skilled in the art to practice the invention, the scope of which is indicated by the appended claims.

What I claim as my invention is:

1. Inside-outside trim comprising a pre-assembled frame consisting of a pair of vertical jamb members and a pair of horizontal members joined together at their ends to form a rectangular open frame for insertion as a unit into the opening of previously constructed window framing from the weather side thereof, said members being formed of sheet metal and having their weather side and room side edges shaped outwardly and reversely to provide channel shaped moldings each having an outer wall and an inner wall generally perpendicular to the plane of the frame and a vertical wall connecting said inner and outer wall, the outer walls of said moldings at the weather side having integral vertical outwardly extending nailing flanges continuous throughout the length of said moldings and dimensioned to extend outwardly of the window opening, the nailing flanges at the ends of one pair of said members extending longitudinally beyond the ends of the moldings a distance substantially equal to the width of the nailing flanges on said other pair of members, whereby said one pair of members have nailing flange portions located substantially in line with the nailing flanges of said other members, the outer walls of said moldings at the room side defining a continuous surface around the frame dimensioned to pass through the window opening, the vertical wall connecting the inner and outer walls of said room side moldings being spaced from the said nailing flange a distance greater than the width of window framing to extend inwardly beyond the room side edge of such framing when said frame is fully inserted therein.

2. Inside-outside trim comprising a pre-assembled frame consisting of a pair of vertical jamb members and a pair of horizontal members joined together at their ends to form a rectangular open frame for insertion as a unit into the opening of previously constructed window framing including

vertical studs at the sides of such opening from the weather side thereof, said members being formed of sheet metal and having their weather side and room side edges shaped outwardly and reversely to provide channel shaped moldings each having an outer wall and an inner wall generally perpendicular to the plane of the frame and a vertical wall connecting said inner and outer wall, the outer walls of said moldings at the weather side having integral vertical outwardly extending nailing flanges continuous throughout the length of said moldings and dimensioned to extend outwardly of the window opening, the nailing flanges at the ends of said horizontal members extending longitudinally beyond the ends of the moldings a distance substantially equal to the width of the nailing flanges on said other pair of members, whereby said pair of horizontal members have nailing flange portions located in line with the nailing flanges of said other members, adapted to be nailed to the studs at the sides of the opening in the window framing.

3. A pre-assembled window frame designed for insertion as a unit into the opening of previously constructed window framing from the weather side thereof, said frame comprising a pair of vertical jamb members, a horizontal head member, and a horizontal sill member, said members being rigidly interconnected at their corners to form a rectangular frame, said members being formed of sheet metal and comprising webs generally perpendicular to the plane of the frame, said webs having their weather and room side edge portions shaped outwardly and reversely to provide channel shaped moldings each having an inner wall and an outer wall generally perpendicular to the plane of the frame and a vertical wall connecting the inner and outer wall of each molding, the outer walls of said moldings at the weather side having integral vertical outwardly extending nailing flanges continuous throughout the length of said moldings and dimensioned to extend outwardly of the window opening, said vertical walls at the room side of said frame being spaced from said nailing flanges a distance greater than the width of window framing to extend inwardly beyond the room side of such framing when said frame is fully inserted therein, and flanges extending from the ends of one of the walls of the room side sill molding and bent across the ends thereof to form end closure walls for said room side sill molding and thereby provide a plaster stop continuous around the sides and bottom of said frame.

4. A pre-assembled window frame designed for insertion as a unit into the opening of previously constructed window framing from the weather side thereof, said frame comprising a pair of vertical jamb members, a horizontal head member, and a horizontal sill member, said members being rigidly interconnected at their corners to form a rectangular frame, said members being formed of sheet metal and comprising webs generally perpendicular to the plane of the frame, said webs having their weather and room side edge portions shaped outwardly and reversely to provide channel shaped moldings each having an inner wall and an outer wall generally perpendicular to the plane of the frame and a vertical wall connecting the inner and outer wall of each molding, the outer walls of said moldings at the weather side having integral vertical outwardly extending nailing flanges continuous throughout the length of said moldings and dimensioned to extend outwardly of the window opening, said

vertical walls at the room side of said frame being spaced from said nailing flanges a distance greater than the width of window framing to extend inwardly beyond the room side of such framing when said frame is fully inserted therein, and flanges extending from the ends of one of the walls of the room side sill molding and bent across the ends thereof to form end closure walls therefore, the lower ends of the room side jamb moldings resting upon and being closed by the inner walls of the room side sill molding.

5. A pre-assembled window frame designed for insertion as a unit into the opening of previously constructed window framing from the weather side thereof, said frame comprising a pair of vertical jamb members, a horizontal head member, and a horizontal sill member, said members being rigidly interconnected at their corners to form a rectangular frame, said members being formed of sheet metal and comprising webs generally perpendicular to the plane of the frame, said webs having their weather and room side edge portions shaped outwardly and reversely to provide channel shaped moldings each having an inner wall and an outer wall generally perpendicular to the plane of the frame and a vertical wall connecting the inner and outer wall of each molding, the outer walls of said moldings at the weather side having integral vertical outwardly extending nailing flanges continuous throughout the length of said moldings and dimensioned to extend outwardly of the window opening, said vertical walls at the room side of said frame being spaced from said nailing flanges a distance greater than the width of window framing to extend inwardly beyond the room side of such framing when said frame is fully inserted therein, the inner walls of the channel shaped moldings of said head member having openings therein bounded at one side thereof by the vertical walls of said moldings, the webs at the upper ends of said jamb members being cut away to leave channel shaped molding portions extending upwardly through the openings in the inner walls of the moldings of said head member and abutting the inner surfaces of the outer walls thereof, the outer wall of the moldings of said head member constituting end closures for the upper ends of the moldings on said jamb members, and the outer walls of the moldings on said jamb members constituting end closures for the moldings on said head member.

6. A pre-assembled window frame designed for insertion as a unit into the opening of previously constructed window framing from the weather side thereof, said frame comprising a pair of vertical jamb members, a horizontal head member, and a horizontal sill member, said members being rigidly interconnected at their corners to form a rectangular frame, said members being formed of sheet metal and comprising webs generally perpendicular to the plane of the frame, said webs having their weather and room side edge portions shaped outwardly and reversely to provide channel shaped moldings each having an inner wall and an outer wall generally perpendicular to the plane of the frame and a vertical wall connecting the inner and outer wall of each molding, the outer walls of said moldings at the weather side having integral vertical outwardly extending nailing flanges continuous throughout the length of said moldings and dimensioned to extend outwardly of the window opening, said vertical walls at the room side of

said frame being spaced from said nailing flanges a distance greater than the width of window framing to extend inwardly beyond the room side of such framing when said frame is fully inserted therein, and flanges extending from the ends of one of the walls of the room side sill molding and bent across the ends thereof to form end closure walls for said room side sill molding, the inner walls of the room side head molding having openings therein bounded at one side thereof by the vertical walls of said moldings, the webs at the upper ends of said jamb members being cut away to leave molding portions extending upwardly through the openings in the inner walls of the room side head molding and abutting the inner surfaces of the outer walls thereof, the outer wall of the room side head molding constituting end closures for the upper ends of the room side jamb moldings and the outer walls of the room side jamb moldings constituting end closures for the room side head molding, thereby providing a plaster stop at the room side of said frame which is continuous completely around said frame.

7. Structure as defined in claim 6 comprising means extending transversely across the ends of the weather side molding of all of said members and constituting end closures therefor.

8. A pre-assembled window frame designed for insertion as a unit into the opening of previously constructed window framing from the weather side thereof, said frame comprising a pair of vertical jamb members, a horizontal head member, and a horizontal sill member, said members being rigidly interconnected at their corners to form a rectangular frame, said members being formed of sheet metal and comprising webs generally perpendicular to the plane of the frame, said webs having their weather and room side edge portions shaped outwardly and reversely to provide channel shaped moldings each having an inner wall and an outer wall generally perpendicular to the plane of the frame and a vertical wall connecting the inner and outer wall of each molding, the channel shaped molding at the weather side of said sill member extending beyond the plane of the vertical walls of the weather side moldings of said jamb members, flanges extending from the ends of one of the walls of the weather side molding of said sill member and bent across to close the ends of said last named molding, the inner walls at the bottom of the weather side moldings of said jamb members abutting the upper surface of the inner wall of the weather side molding of said sill member, the outer walls of the weather side moldings of said jamb members extending downwardly beyond the lower end of the inner walls thereof and overlapping the ends of the weather side molding of said sill member.

9. A pre-assembled window frame designed for insertion as a unit into the opening of previously constructed window framing from the weather side thereof, said frame comprising a pair of vertical jamb members, a horizontal head member, and a horizontal sill member, said members being rigidly interconnected at their corners to form a rectangular frame, said members being formed of sheet metal and comprising webs generally perpendicular to the plane of the frame, said webs having their weather and room side edge portions shaped outwardly and reversely to provide channel shaped moldings each having an inner wall and an outer wall generally perpendicular to the plane of the frame,

dicular to the plane of the frame and a vertical wall connecting the inner and outer wall of each molding, the outer walls of said moldings at the weather side having integral vertical outwardly extending nailing flanges continuous throughout the length of said moldings and dimensioned to extend outwardly of the window opening, the room side molding of said sill member extending into the room further than the room side moldings of said jamb members, and flanges extending 10 from the ends of one of the walls of the room side molding of said sill member and bent to lie across and constitute end closures for said last mentioned moldings

10. Combination inside-outside trim for window openings comprising vertical jamb members and horizontal head and sill members, all of said members being formed of sheet metal and comprising webs generally perpendicular to the plane of the window opening, both the weather 20 and room side edge portions of all of said webs being shaped outwardly and then reversely to provide channel shaped moldings having inner and outer walls connected by vertical walls, the corners of all of said members being interlocked to form a rigid rectangular frame, the end of one of said head and jamb members having its web cut away to leave channel shaped molding portions extending longitudinally beyond the end of its web, the adjacent end of the other of said head 30 and jamb members having both the inner walls of its weather and room side moldings cut away to provide slots in the inner walls opening at the end thereof and extending to said vertical walls, 35 said slots being shaped to receive and interfit with the corresponding longitudinally extending chan-

5

nel shaped molding portions of said one member, the end portions of the outer walls of the moldings of said head and jamb members constituting abutments and end closures for the moldings of said jamb and head members respectively.

11. Structure as defined in claim 10 in which the lower ends of said jamb members rest upon the horizontal sill portion of the sill member at the ends thereof and are connected thereto by tongue and slot elements, and in which the ends of the room side molding of said sill member includes closure elements provided by flanges bent across the ends thereof from one of the walls of said molding.

12. Structure as defined in claim 10 in which the webs of both said head and jamb members are shaped to provide inwardly extending hollow ribs, the cut away portion of the web of said one member being shaped to provide a notch to receive the rib of said other member.
